(57) **CLAIM**

The ornamental design for an apparatus for skin treatment, as shown and described.

DESCRIPTION

FIG. 1 is a front perspective view of an apparatus for skin treatment;

FIG. 2 is a bottom planar view thereof;

FIG. 3 is a top planar view thereof;

FIG. 4 is a left-side elevational view thereof, the right-side elevational view being a mirror image thereof;

FIG. 5 is a front elevational view thereof; and,

FIG. 6 is a rear elevational view thereof.

In the drawings, the broken lines depict unclaimed subject matter only and form no part of the claimed design.

1 Claim, 5 Drawing Sheets
